CLOSURE FOR COLLAPSIBLE TUBES AND
THE LIKE

Charles J. Jesnig, Philadelphia, Pa.

Application September 27, 1932.
Serial No. 635,019

9 Claims. (Cl. 221—60.)

A principal object of the present invention is the provision of a novel form of closure for receptacles such as the collapsible tubes or the like which are commonly employed for holding tooth-paste, shaving cream, and other generally similar plastic materials and from which the said materials are ejected as required by suitable pressure applied to the body of the tube.

A further object of the invention is the provision of a closure for a tube of the character aforesaid which is effective to completely seal the tube when closed but which may be readily operated to permit the ejection from the tube of any desired quantity of the contained material; which embodies, among other things, a sealing element made of non-metallic material through the medium of which the actual sealing of the neck of the tube is effected, said sealing element being interposed between said neck which is desirably integral with the tube body and a movable cap carried by and supported from the neck, whereby metal to metal contact is avoided between the adjacent parts of the cap and the end of the neck between which the plastic material is extruded.

A still further object of the invention is the provision of a closure of the character aforesaid which can be easily and cheaply manufactured, which is efficient in operation, embodies no loose parts liable to come off or be displaced when the device is in use, which is adapted to permit the exudation of the material in a constant stream so long as suitable pressure is applied to the body of the tube, which merely requires the screwing down or unscrewing of the cap portion of the device to seal or unseal the closure, and which is of neat appearance and not liable to get out of order or become damaged under the conditions of use to which devices of this character are necessarily subjected.

Other objects, advantages and novel features of design, construction and arrangement comprehended by the invention are hereinafter more particularly pointed out or will be apparent to those skilled in the art from the following description of a preferred embodiment thereof as illustrated in the accompanying drawing.

In the said drawing, Fig. 1 is an elevation of a collapsible tube provided with the closure of my invention; Fig. 2 is an enlarged fragmentary central section of the closure and adjacent portion of the tube shown in Fig. 1 with the closure cap in closed position, and Fig. 3 is a similar view with the cap in open position; Fig. 4, on the same scale as Figs. 2 and 3, is a composite view, partial-

ly in elevation and partially in central section, showing the cap as it appears prior to assembly with the other parts, the non-metallic sealing element and the neck and upper end of the tube; Fig. 5 is a top plan view of the neck and upper portion of the tube prior to assembly with the other said parts, and Fig. 6 is an enlarged perspective view of the sealing element. Throughout the drawing the same characters of reference are used to designate the same parts.

Referring now more particularly to the drawing, the tube is of usual construction and thus comprises a generally cylindrical body T of thin metal such as aluminum or zinc having one end t' formed integral therewith and closed at its opposite end by folding the metal over upon itself after the paste or other material which the tube is to contain has been introduced therein. As usual, the end t' is of generally conical form and in accordance with the present invention is provided with an axially extending neck 1 having a bore 2 of suitable diameter, the neck being preferably cast or otherwise formed integral with the tube. The neck terminates in a conical extremity 3 disposed beyond the outer end of the bore 2, the surface 3' of this conical portion forming a seat for the sealing element 5 hereinafter more particularly described. This conical portion is pierced with one or more generally inwardly extending apertures 6 which thus form passages from the bore 2 within the body of the neck through which material contained in the tube can pass to the conical surface 3'. Desirably and as best shown in Fig. 5, these passages 6 are of arcuate contour when viewed endwise and, when two of them are provided, are disposed in opposed diametric relation on opposite sides of the axis of the neck and while I prefer to provide passages of the general character of those shown, other forms of passage may be utilized if desired so long as the same are effective to permit the material in the body of the tube to freely reach the conical surface at the end of the neck, which latter is preferably truncated as at 7 a short distance below what would otherwise be its apex.

The neck is provided below its conical surface 3' with external screw threads 8 and also, preferably, with an undercut peripheral groove 9 disposed between the inner extremity of the threads and the base of the neck. In accordance with the customary methods of manufacture of articles of this general character, the neck may be initially formed by casting to an external diameter equal to or slightly greater than the corre-

sponding diameter of the threads and the latter then rolled therein in the well known way; simultaneously with this operation, the groove 9 can also be readily rolled or otherwise suitably formed 5 in the neck which is preferably initially made of the same outside diameter in the zone to be occupied by the groove as in the zone to be subsequently occupied by the threads to enable the neck to be readily withdrawn from the mold in 10 which it is formed. In certain circumstances it is also possible by using a two part mold to cast the threads 8 and groove 9 directly in the neck, thus avoiding the separate rolling or other operation incident to forming them therein. 15 The passages 6 are also desirably formed in the neck when the latter is cast through the provision of suitable cores in the mold but if preferred the outer end of the neck may be initially cast solid and the passages then drilled, 20 broached, or otherwise formed therein in any convenient way.

The cap 10, which is operatively telescoped over the neck, is initially formed substantially as shown in Fig. 4, and thus embodies a depending hollow cylindrical skirt 11 above which are internal threads 12 adapted for cooperation with the threads 8 on the neck while above the threads the interior of the cap may be formed to provide a short annular or cylindrical surface 13 beyond 25 which the inner surface of the cap is made conical as at 14 in correspondence or substantial correspondence with the conical surface 3 of the neck, the inclination of the respective surfaces being thus substantially identical. Externally, 30 the body of the cap may be of generally cylindrical contour but its upper outer surface is preferably inwardly inclined in general correspondence with the inclined surface 14, the cap terminating in a flat annular surface 15 surrounding 35 a central outlet 16 of slightly greater diameter than the surface 7 of the neck.

Mention has been made of the sealing member 5 which, when the closure is assembled, is interposed between the conical surfaces 3' and 14 of 40 the neck and cap respectively. This member is formed of celluloid or other generally similar slightly yieldable material unaffected by the paste or other substance which the tube is designed to contain and is in the form of a truncated hollow 45 cone, as best shown in Fig. 6. The wall of the sealing element is relatively thin and the opening in its upper end is of only very slightly greater diameter than the diameter of the surface 7 of the neck so that when the element is seated on the 50 latter it will depend from the end of the neck a sufficient distance to cover or substantially cover the conical surface 3' and in any case the mouths of the passages 6 therein. The element is preferably 55 so formed, however, that the angular inclination of its wall towards its central axis is slightly greater than the corresponding inclination of the surfaces 3' and 14 so that when the element is seated on the former as just described 60 and not constrained into intimate engagement therewith by the pressure of the cap as herein-after explained, it will flare outwardly from the surface 3 to a slight extent so that a very small clearance, diminishing toward the apex of the 65 coned surface 3', will exist between said surface 70 and the sealing element.

The cap, neck and sealing element having been constructed substantially as described are assembled as indicated in Fig. 4, that is, by first seating the element on the surface 3' of the neck 75 and then screwing the cap downwardly thereover

until its depending skirt 11 comes into alignment with the groove 9. To prevent the subsequent removal of the cap by the user, the free edge of the skirt is then crimped inwardly as shown in Figs. 2 and 3 at 11', the parts being so proportioned that after this is done the cap is capable of being screwed down to compress the sealing element between the conical faces 14 and 3' as shown in Fig. 2 or unscrewed for a limited distance as shown in Fig. 3, the extent of outward travel of the cap being of course limited by the engagement of the flange with the upper or outer edge of the undercut groove 9.

It will thus be apparent that when the cap is screwed down as shown in Fig. 2, the sealing element is forced into intimate engagement with the conical surface 3' thus closing the passages 6 and preventing any exudation of paste from the tube, the material of which the element is made being sufficiently yielding to permit its being 90 pressed snugly against said surface through the pressure exerted on the element by the conical inner surface 14 of the cap. When the cap is unscrewed, however, the sealing element at once 95 springs back to its normal shape thus separating its inner face from the adjacent surface 3', and if pressure be now applied to the body of the tube in the usual way, the paste extruded from the passages 6 carries the sealing element upwardly until its further movement is arrested by 100 engagement with the inner surface of the cap, the element then occupying a position slightly separated from the conical surface 3' and thus affording a hollow conical passage extending 105 entirely about said surface and beneath the element through which the paste can pass upwardly 110 through the opening at the upper end of the sealing element and thence through the outlet 16 in the cap from which it issues in a substantially round stream so long as the pressure on the body 115 of the tube is continued. Upon release of the pressure further exudation of the paste is arrested or substantially so and the cap may then be screwed down to its initial or closed position 120 thus bringing the sealing element again into intimate engagement with the conical surface 3' and positively sealing the tube against further passage 125 of the paste or other material therefrom.

Consequently in operating the closure it is only necessary to unscrew the cap and press 130 on the tube when it is desired to force a quantity of contained material therefrom and to turn the cap back to initial position when it is desired to positively seal the tube against further flow thereof. Under all conditions contact 135 between the cap and the contents of the tube is prevented save as the contents momentarily pass over the margin of the outlet 16 in the cap, while due to the tendency of the sealing element to spring away from the conical surface 3' whenever the pressure of the cap is removed, sticking of the element on the neck and consequent necessity for applying pressure to the tube additional to that which would normally be required to extrude the paste therefrom is avoided. Thus 140 whenever the cap is screwed home, a positive sealing of the tube is brought about and since the sealing element, which of course under these conditions is in contact at the mouths of the 145 passages 6 with the material contained in the tube, is preferably made of a material inert to the latter, all danger of contaminating the paste in the tube is obviated irrespective of the length of the time the seal may be maintained. Moreover, due to the construction of my improved 150

closure the material in the tube, as stated, is extruded from the outlet 16 in the cap in a substantially round stream and can thus be readily applied to a toothbrush or other article in an effective way.

While I have herein described one form of my invention with considerable particularity I do not thereby desire or intend to specifically limit myself to any precise details of design, construction or assembly of the various parts as the same are capable of modification in minor particulars as will be readily understood by those familiar with the art without departing from the spirit and scope of the invention as defined in the appended claims.

Having thus described my invention, I claim and desire to protect by Letters Patent of the United States:

1. In combination, a collapsible tube having a neck provided with a conical end surface and a passage extending therefrom to the interior of the neck, a cap having an inner conical surface seating over the end of the neck and a discharge outlet, said cap arranged for movement toward and away from the conical surface of the neck, and a yieldable sealing element interposed between said conical surfaces free to move longitudinally thereof in correspondence with the movement of the cap.

2. In combination, a collapsible tube having an exteriorly threaded neck terminating in a conical surface and having a passage leading therefrom to its interior, an internally threaded cap seating over the end of the neck provided with an inner conical surface and an outlet at the smaller end thereof, and a yieldable conical sealing element loosely interposed between said conical surfaces and movable axially into engagement with the conical surface of the neck when the cap is screwed down on the latter to thereby seal the passage therein against extrusion of the material contained in the tube.

3. In combination, a collapsible tube having an exteriorly threaded neck terminating in a conical surface and having a passage leading therefrom to its interior, an internally threaded cap seating over the end of the neck provided with an inner conical surface and an outlet at the smaller end thereof, and a non-rigid conical sealing element loosely interposed between said conical surfaces movable axially into engagement with the conical surface of the neck when the cap is screwed down on the latter to thereby seal the passage therein against extrusion of the material contained in the tube and, when the cap is unscrewed for a limited distance, operative to move axially away from said surface under the pressure of the material extruded from the tube to thereby afford for said material a hollow conical passage to the outlet in the cap between the surface of the neck and the sealing element.

4. In combination, a collapsible tube having an externally threaded neck terminating in a truncated conical surface and a passage leading from said surface to the interior of the neck, a conical sealing element of yielding material having an opening in its smaller end adapted to seat over the conical end of the neck, and a cap having internal threads cooperative with the threads on the neck, an inner conical surface adjacent its extremity and an outlet at the smaller end of said surface, said cap when screwed inwardly on the neck operating to force the sealing element into intimate contact with the conical surface thereof to thereby seal the passage

therein, said element when the cap is unscrewed being free to move axially outward with respect to the neck to afford a passage between the element and the neck for the material in the tube when extruded therefrom through the passage in the neck by pressure on the tube.

5. In combination, a collapsible tube having an externally threaded neck terminating in a truncated conical surface and a passage leading from said surface to the interior of the neck, a conical sealing element of yielding material having an opening in its smaller end adapted to seat over the conical end of the neck, and a cap having internal threads cooperative with the threads on the neck, an inner conical surface adjacent its extremity and an outlet at the smaller end of said surface and means for limiting the extent of outward movement of the cap on the neck, said cap when screwed inwardly on the neck operating to force the sealing element into intimate contact with the conical surface thereof to thereby seal the passage therein, said element when the cap is unscrewed being free to move axially outward with respect to the neck to afford a passage between the element and the neck for the material in the tube when extruded therefrom through the passage in the neck by pressure on the tube.

6. In combination, a collapsible tube having a neck terminating in a truncated conical surface and provided with external screw threads between said surface and the body of the tube, a cap seating on the neck and having internal threads cooperative with those on the neck, said cap comprising an inner conical surface of angularity corresponding to the conical surface of the neck and an outlet at the small end thereof, and a conical sealing element of yieldable material interposed between said conical surfaces, the wall of the element being normally of greater angular inclination toward its axis than said surfaces, said element being free to move axially into intimate engagement with the conical surface on the neck when the cap is screwed inwardly thereon and to spring outwardly from the neck when the pressure of the cap on the element is released by screwing it in the opposite direction.

7. In combination, a collapsible tube having a neck terminating in a truncated conical end surface and having screw threads interposed between said surface and the base of the neck and a passage leading from said surface to the interior thereof, a cap seating over the neck and having internal threads cooperating with those on the latter whereby the cap may be moved axially of the neck, said cap also having an inner conical surface of corresponding inclination to that of the neck and terminating in an outlet opening at the outer extremity of the cap, means for limiting axial movement of the cap outwardly of the neck, and a conical sealing element formed of yieldable material interposed between said conical surfaces, the normal angular inclination of the wall of the element being greater than that of said surfaces, said element being free to move axially to intimately engage the conical surface of the neck to seal the passage therein when pressed thereagainst by an axial movement of the cap toward the tube and when the pressure of the cap on the element is relieved by moving the cap away from the tube body to spring outwardly from said surface and afford a passage beneath the element for material ex-

truded from the neck by pressure on the body of the tube.

8. In combination, a collapsible tube having a neck terminating in a truncated conical surface and having an axially offset passage leading to its interior, a cap seated on the neck, axially movable with respect thereto and having an internal conical surface terminating in an outlet opening at its outer end, and a non-metallic non-rigid conical sealing element loosely interposed between the cap and the neck and compressible between both said surfaces by a movement of the cap toward the neck to thereby seal the passage in the latter.
